SPRAY GUN ATTACHMENT

Bernard C. Amore, Cleveland, Ohio

Application April 22, 1947, Serial No. 743,150

8 Claims. (Cl. 15—128)

1

My invention relates to painting devices and more particularly to a brush attachment for spray guns. My invention is particularly directed to a novel brush and mounting means providing for attachment to the usual and well-known spray guns used for spraying paint.

An object of my invention is to provide a novel and efficient means to a spray gun for the brushing of the paint as it is sprayed from the gun.

Another object is the provision of a guard or shield for the diffused spray of paint coming from a spray gun, which guard or shield is of bristle material adapted for spreading the paint upon the surface to which the paint has been sprayed.

Another object is the provision of a simple and yet convenient means of attaching a brush to a spray gun.

Another object is the provision for mounting brush bristles around four sides of the nozzle of a spray gun whereby the brush bristles direct the paint being sprayed and also brush the material along the surface thus sprayed.

Another object and a fuller understanding of my invention may be had by referring to the following description and claims, taken in conjunction with the accompanying drawing, in which:

Figure 1 is a side view of a spray gun with my brush attachment mounted thereto;

Figure 2 is a view taken through the brush of my device and looking in the direction of the arrows 2—2 of Figure 1;

Figure 3 is a detailed view illustrating the mounting of my device and is a cross-sectional view through the line of the arrows 3—3 of Figure 1; and

Figure 4 is an exploded view of my brush attachment removed from the spray gun and shows the brush member removed from the bracket member.

In the several views of the drawing, the reference character 11 denotes generally the spray gun. This spray gun is of the usual or orthodox type and has a body 12 and a pistol handle 13 extending at an angle from the body portion 12. There is provided an air inlet 28 connected to the lower end of the pistol handle 13 and there is provided a paint or liquid inlet 38 leading into the body 12 of the gun. A trigger 14 operates the valve mechanism of the gun in the usual manner. The upper end of the trigger 14 is forked to provide the forked end 15, the forked end 15 straddling the body 12 and the upper end of the forked end 15 of the trigger being pivotally carried by a bolt 17 extending through the body of the gun.

2

A cylinder sleeve 16 on the bolt 17 engages in opposite holes formed in the forked end 15 and thus the trigger 14 pivots on the bolt 17 and sleeve 16 so that by reciprocating the lower end 5 of the trigger 14 the valve mechanism of the gun is operated. The gun 11 has a nozzle portion 31 at its forward end. This nozzle 31 is in the usual form having air and paint or liquid outlets arranged to provide a spray of paint or other liquid 10 forwardly from the gun upon operation of the trigger 14 to its operating position.

The bracket member, denoted generally by the reference character 18, is adapted to fit over, and be attached to, the spray gun. The bracket member 18 is preferably made of sheet metal such as light sheet steel and will flex slightly to adapt itself to engagement on the gun. The bracket member 18 has two spaced and generally parallel side walls which engage on the opposite sides of 15 the spray gun. There is an upper portion 19 of the spaced side walls which are on opposite sides of the body 12 of the spray gun and there is a lower portion 20 of the spaced side walls which are engaged on opposite sides of the pistol handle 20 25 13 of the spray gun. To generally conform to the outline of the gun the lower portion 20 of the bracket is extended at an angle to the upper portion 19, the upper portion 19 thus fitting over the body of the gun and the lower portion 20 thus fitting along the pistol handle of the gun. The two spaced side walls of the bracket 18 are joined by a rear or back wall 21 along the rear edge of the lower portion 20 of the spaced side walls. Thus the upper portion 19 of the spaced 30 35 side walls has two separate or forked portions and the lower portion 20 is joined so that the two side walls along the back of the pistol handle are joined by the rear wall 21. As shown in Figures 1 and 4 the spaced side walls composed of upper portion 19 and lower portion 20 are generally parallel to each other. The rear wall 21 is somewhat curved or circulate so as to provide a smooth and comfortable surface for the hand of the operator holding the gun and brush attachment together. There is a slight spring in the 40 45 50 curved rear wall 21 to permit the bracket to have its side walls slightly flexed in applying the bracket to the gun. The resiliency of the rear wall 21 and the bracket generally is set as to hold the bracket in snug and firm engagement on the gun after mounting.

The upper portion 19 of the two spaced walls has two aligned holes 25 which receive the bolt 17 carrying the trigger 14. The holes 25 are of 55 a diameter to permit the bolt 17 to extend through

but are not of sufficient diameter to permit the sleeve 16 to extend through. As shown in Figure 3 the side walls of the bracket are firmly clamped to the body 12 of the gun by the bolt 17 extending through the forked end 15 of the trigger, through the body 12 and through the upper portion 19 of the spaced side walls of the bracket. To prevent binding of the trigger upon turning the wing nut 26 on the bolt 17 and drawing of the head 27 of the bolt 17 inward, it is provided that the side walls 19 are pressed inwardly upon the sleeve 16. Thus the bracket is tightly engaged to the spray gun body and yet the forked end 15 of trigger 14 is not tightly bound thereby and it may freely rotate on the shaft provided by the sleeve 16.

At the forward end, that is the end nearest the nozzle, of the two spaced side walls the outwardly extending walls 22 diverge outwardly at a right angle to the upper portion 19 of the bracket. The side walls of the bracket then bend at another right angle at the outer extreme of the outwardly extending walls 22 to form the parallel clamping walls 23. Thus as seen in the several views of the drawing, and particularly in Figure 4 thereof, the bracket 18 comprises two identical portions spaced from each other and joined at one end by the rear wall 21. The clamping walls 23 may be moved slightly toward and away from each other as desired. The walls 23 are a continuation of the spaced side walls of the upper portion 19, the clamping walls 23 being spaced farther apart than the other parts of the bracket by reason of the outwardly extending wall portions 22. The lower and inner portions of the outwardly extending walls 22 are cut away at 28 as indicated in Figures 2 and 4. The cut away portion 28 provides for the ready mounting of the bracket 18 over the body 11 and particularly for the slipping of the portions 22 over the nozzle 31 where the paint inlet 30 enters the gun body, the cut-away portion 28 accommodating the paint inlet 30 and the hose (not shown) attached thereto.

Two pairs of aligned holes 24 are provided in the parallel clamping walls 23, one pair of aligned holes 24 being in the upper portion and the other pair of aligned holes 24 being in the lower portion.

The brush member of my device, denoted generally by the reference character 33, is in a generally rectangular form in cross section. It also has a rectangular shaped open space therein, the open space being bounded on four sides by the body of the brush. The base of the brush is comprised of an outer rectangular shell 34, preferably made of sheet metal formed to the desired shape, and an inner rectangular shell 35, also preferably made of sheet metal formed to desired shape. The inner shell 35 is somewhat smaller than the outer shell 34 and the ends of bristles 40 are clamped or firmly bound between the inner and outer shells 34 and 35. A suitable mounting substance such as hard rubber or plastic embeds the inner ends of the bristles within the shells 34 and 35 so that the bristle portion 40 becomes firmly bound within the base formed by shells 34 and 35.

Two pairs of aligned holes 36 are provided in the brush member to extend through the opposite walls of the shells and confine bristle portions. The upper holes 36 in the brush member are in alignment with the upper holes 24 of the bracket member and the lower pair of holes 36 in the brush member are in alignment with the lower pair of holes 24 in the bracket member.

Two long bolts 37 having heads 38 and wing nuts 39 provide for the clamping and securement of the brush members between and to the clamping walls 23 of the bracket member. The bolts 37 extend through the brush members and clamping walls 23 as indicated in the figures of the drawing, and by turning the wing nuts 39 down to draw the heads 38 inwardly the brush member is firmly anchored to the bracket member.

10 To assemble my brush attachment to a spray gun the bracket member 18 is moved forwardly against the back of the spray gun and the lower portion 20 of the bracket is pressed firmly upon the pistol handle 13 until the rear wall 21 engages the pistol handle 13. The upper portion 19 is thus on both sides of the body 12 and in loose engagement with the body 12. The bolt 17 that carries the trigger 14 is inserted to the position shown in Figure 3 and the wing nut 26 tightened down. Thus the two side walls of the upper portion 19 are firmly anchored and secured to the body of the gun. By reason of the disposition of the sleeve 16 around the bolt 17, the wing nut 26 may be tightened down but the trigger 14 is not tightly bound thereby.

Next, the brush member 33 is placed in position by moving the base of the brush member between the two opposite clamping walls 23 of the bracket. The longer sides of the rectangular shaped base of the brush member are placed adjacent the long clamping walls 23. Bolts 37 are then inserted through the aligned holes 24 and 36 and the wing nuts 39 applied and tightened down. The brush member is thus tightly clamped between and secured to the clamping walls 23 of the bracket 18. In this position the large rectangular open space in the bristle portion 40 of the brush member surrounds the nozzle 31 of the spray gun. As seen in the drawing, the brush portion 40 forms a shield or guard around four sides of the nozzle and acts to confine the spray discharged from the nozzle from spreading too far sideways.

To disassemble the device the process is repeated in reverse. The wing nuts 39 are removed and the bolts 37 withdrawn. The brush member is thus taken from the bracket. The bracket is removed from the gun by removing the wing nut 26 and withdrawing the bolt 17. By pulling back on the bracket it is disengaged from the spray gun and the entire device is thus disassembled from the gun.

It will be noted from the drawings and description, that this device permits the spray gun to be used in the usual manner to spray a surface and also permits the brush to brush across the sprayed surface in the usual manner. The brush bristles provide a shield to prevent widespread diffusion of the paint spray. In operation it has been found that great advantages in operation in painting may be had by holding the device with the forward end of the bristles removed a short distance such as two or three inches from the surface being painted and moving the device parallel to the surface at the spaced position while spraying paint. Then after sufficient paint has been applied to the surface by spraying, the gun is moved forwardly to bring the bristles in contact with the surface being painted and the device moved back and forth along the surface to spread the paint with the bristles. This device combines the advantages of both a spray gun and brushes and permits both to be used substantially simultaneously. In outdoor painting such as painting a side of a house,

it has been found that the wide diffusion of paint spray ordinarily makes paint spraying too difficult and inconvenient for use, the spray being spread diffused around the surrounding atmosphere. However, with my device the spray is confined to a less local area, is directed to where application of paint is desired, and the paint may be brushed as and where needed.

It is understood of course that the word "paint" as used in the description and claims covers any liquid or semi-liquid substance ordinarily sprayed or adapted to be sprayed from spray guns.

Although I have described my invention in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A brush device for a spray gun, said spray gun having a pistol handle, a gun body disposed at an angle to said pistol handle, an operating trigger engaging a pivot member carried by the said gun body, and a spray nozzle extending from said gun body, comprising in combination a brush member, said brush member having a base portion and a bristle portion, said base portion having an open space therein and having said bristle portion extending therefrom around said open space, said open space extending through said bristle portion from said base portion to the opposite end of said bristle portion, a bracket member for engaging said brush member to said spray gun, said bracket member having a pair of spaced side walls, said side walls having upper portions adapted to embrace said gun body therebetween and having lower portions adapted to embrace said pistol handle therebetween, an end wall connecting said lower portions of said side walls and adapted to engage the back of said pistol handle, a pair of clamping portions adapted to engage and embrace therebetween the base portion of said brush member, and connecting portions extending out from, and at an angle to, said side walls, respectively, and connecting said side walls and said clamping portions, respectively, of the bracket member, first securing means adapted to secure said side walls to said pivot member, and second securing means adapted to secure said clamping portions to the base portion of said brush member, the arrangement of the bracket member and brush member providing for the positioning of said brush member at said spray nozzle for brushing paint sprayed therefrom.

2. The combination of a brush member having an open space provided therein for permitting a liquid spray to pass therethrough, said liquid spray being producible by a spray gun having a spray nozzle and a handle, and a bracket member for securing said brush member to said spray gun, said brush member having a base portion and a bristle portion carried by the base portion, said base portion and bristle portion being arranged around said open space from said base portion to the opposite end of said bristle portion to provide open communication between the spray nozzle and the surface being sprayed, said bracket member having spaced side walls adapted to engage the opposite sides of said spray gun and having a rear wall joining said spaced side walls at a distance from said brush member, said

spaced side walls having outwardly extending portions and brush-member clamping portions carried by said outwardly extending portions, said bracket member being adapted to fit over said spray gun with said rear wall positioned adjacent the handle of the gun and the said clamping portions positioned adjacent the spray nozzle, first means adapted to secure said bracket to said gun and second means adapted to secure said clamping portions to said base portion of said brush member, said second means clamping the base portion between said clamping portions.

3. A brush attachment for a spray gun having a gun body, a nozzle extending forwardly from said gun body, a pistol handle extending rearwardly from said gun body, and a trigger having a pivot connection with said gun body, said brush attachment comprising a bracket member having spaced side walls adapted to extend along, and engage the sides of, said gun body and pistol handle, a rear wall connecting the rear edges of the said side walls adjacent said pistol handle, and brush-member engaging walls connected to, and displaced outwardly from the planes of, said spaced side walls, and a brush member having a base portion and a bristle portion, said base portion being disposed on opposite sides of an open space and said bristle portion extending from said base portion to the forward end of said bristle portion on the opposite sides of said open space, means adapted to clamp said base portion between said engaging walls of the bracket member to position said gun nozzle in said open space and to extend the bristle portion forwardly from said nozzle, and means adapted to secure the said side walls of the bracket member to the gun body at said pivot connection.

4. A bracket member for mounting a brush to the body and handle of a spray gun having a gun nozzle, said brush having spaced portions to be mounted on opposite sides of, and surrounding but spaced from, the gun nozzle, comprising sheet metal formed to provide two spaced walls adapted to embrace the body and handle of said spray gun therebetween, said spaced walls being formed to extend along said body and handle forwardly toward said nozzle and extend at their forward edge to diverge outwardly and then extend forwardly to accommodate opposite spaced portions of the brush therebetween, and being joined at their rearward edges, said joined rearward edges being adapted to accommodate said handle, said bracket being adapted to flex from said rearward edges to embrace said gun and brush between said spaced walls.

5. A bracket member for mounting a brush to a spray gun, said gun having a body, a nozzle extended from said body and a pistol handle extended from said body at an angle to the axis of said nozzle, said brush having an open space extending therethrough for accommodating said nozzle and permitting the spray from the nozzle to discharge through the open space, comprising opposite spaced side walls adapted to extend along the sides of said body and pistol handle to embrace the same therebetween, a connecting wall connecting said side walls together along edge portions thereof, said connecting wall securing said side walls together at said edge portions and providing a hand gripping surface cooperating with said pistol handle for handling said spray gun and bracket member, said side walls at the forward end of the bracket member being formed to accommodate said brush at said nozzle

and providing a support for mounting said brush.

6. A bracket member for mounting a brush to a spray gun, said gun having a body, a nozzle extended from said body, a pistol handle extended from said body at an angle to the axis of said nozzle, and a pivot pin for pivotally carrying an operating trigger for said gun, said brush having an open space extending therethrough for accommodating said nozzle and permitting the spray from the nozzle to discharge through said open space, comprising two spaced walls each having an upper portion and a lower portion, the upper portion of said side walls being adapted to extend along the sides of said body, the lower portion of said side walls being disposed at an angle to said upper portion and being adapted to extend along the sides of said pistol handle, a connecting wall connecting the lower portion of said side walls, said connecting wall being resiliently flexible to provide for resilient clamping of said spray gun by said side walls, said connecting wall and lower portion of the side walls having a hand gripping surface cooperative with said pistol handle to permit hand gripping of both the pistol handle and bracket member as a unit, said upper portion of the side walls having aligned openings adapted to accommodate said pivot pin therethrough, said upper portion of the side walls at an end thereof being flanged to provide a support for mounting said brush at said nozzle, the flanged end being disposed at an angle to hold the brush in alignment with, and spaced from, said nozzle.

7. A brush member adapted to be mounted by a mounting bracket on a spray gun having a nozzle, said brush member comprising a rectangular base portion, said base portion having rectangular shell means, the outer walls on opposite sides of said base portion being adapted to engage parallel clamping walls of said mounting bracket, bristles each having a first end carried by said shell means, embedding material for bonding said first end of said bristles to said shell means, said bristles having their opposite ends free and extending from said base portion

around the periphery thereof, said base portion and bristles extending therefrom defining an open space extending parallel to said bristles from said base portion to the said opposite ends of said bristles, said base portion having means carried by its outer walls and disposed laterally of the base portion for accommodating securing means extending laterally outwardly from said base portion for the mounting of the brush member to said parallel clamping walls of the said mounting bracket engaging said outer walls of the base portion.

8. The combination of a brush surrounding a central open space therein adapted to permit a liquid spray to be ejected therethrough, a spray gun having a nozzle for ejecting a liquid spray, said spray gun having a pistol handle disposed at an angle to said nozzle, and a bracket mounted on said spray gun for securing said brush to the gun at the nozzle thereof and aligning the open space of said brush with said nozzle, said bracket having a handle portion, said handle portion having an open side to permit the pistol handle of the gun to be moved therethrough for assembly and disassembly, said handle portion having other sides complementarily fitting and embracing said spray gun nozzle and forming therewith a combined handle for the gripping of said gun and bracket as a unit.
